WINDING MACHINE

Filed August 13, 1923 2 Sheets-Sheet 2

Patented Sept. 21, 1926.

UNITED STATES PATENT OFFICE.

ANTON VAN VEEN, OF HARTFORD, CONNECTICUT, ASSIGNOR TO THE FULLER BRUSH COMPANY, OF HARTFORD, CONNECTICUT, A CORPORATION OF CONNECTICUT.

WINDING MACHINE.

Application filed August 13, 1923. Serial No. 657,043.

My invention relates to the class of machines employed for winding thread, cord or the like, upon a support, and more especially in a manner to give form to the 5 mass so wound, and an object of my invention, among others, is to provide a machine of this class that shall be simple in construction and particularly efficient in operation.

10 A form of machine embodying my invention and in the construction and use of which the objects herein set out, as well as others, may be attained, is illustrated in the accompanying drawings, in which—

15 Figure 1 is a view in front elevation of my improved winding machine, with parts broken away to show construction.

Figure 2 is a top view of the machine.

Figure 3 is a view in elevation looking 20 at the back of the machine.

Figure 4 is a view in end elevation on a plane of section denoted by the dotted line 4—4 of Figure 2.

Figure 5 is a detail view illustrating the 25 construction of the tension and thread breaking device.

In the accompanying drawings the numeral 10 denotes a base comprising part of my improved machine with standards 11 rising therefrom and constituting supports for 30 a driving shaft 12 that is mounted in suitable bearings in said standards. Two driving pulleys 13 are secured to said shaft to receive belts 14—15 arranged, as by crossing 35 one of the belts, to drive the pulleys and hence the shaft 12 in opposite directions, depending upon which belt is upon a certain pulley. Thread form driving pulleys 16 are secured to thread form driving sleeves 40 17 mounted in bearings 18 at the upper ends of the standards 11, the direct bearing of the opposite ends of the driving shaft 12 being in fact in said sleeves. The pulleys 16 are arranged to be driven in opposite 45 direction by the belts 14—15, one of which, as hereinbefore stated, is crossed, said belts being shifted from the pulleys 13 to the pulleys 16, by mechanism to be hereinafter described. Each of the sleeves 17 has a 50 thread form spindle 19 secured thereto and projecting within the sleeve, and a collapsible thread form is secured to each of said spindles.

Each of said thread forms consists of two

jaws 20—21 that are relatively movable 55 toward and away, one from the other. In the special construction herein shown both jaws of each form are supported upon a pivot 22, means being provided for a relative movement of the jaws resembling that 60 of a pair of shears. In the structure shown a shank on the jaw 21 extends into an actuator 24, but no special means are provided for swinging this jaw on the pivot, whereas the jaw 20 has an actuating shank 65 23 extending therefrom into the actuator 24 that has a peripheral groove and is mounted upon the spindle 19, and each actuator has a reciprocating movement longitudinally of 70 the shanks it receives to operate the shank 75 of the jaw 20 to move said jaw toward and away from a jaw 21 in a manner that will be readily understood from an examination of Figure 1. The means for operating said actuator will be hereinafter described. 75

From the above description, taken in connection with the drawings, it will be perceived that there are a plurality of collapsible thread forms (two in the special construction herein shown) one located at each 80 end of the machine.

A thread guide pinion 25 is secured to the driving shaft 12, said pinion meshing with a thread guide gear 26 secured to a thread guide shaft 27 rotatably mounted in bearings in the lower parts of the standards 11 and supported at one end in a bearing 28. This thread guide shaft is threaded to engage a thread guide operating arm 29 secured at one end to a supporting bar 30 of 90 a thread guide frame, said frame comprising the bar 30 and another and similar bar 31 both supported in bearings 32 at opposite ends of the machine. Said thread guide frame also comprises posts 33 secured one 95 to each supporting bar and projecting therefrom, said posts having a coupling bar 34 joining them and comprising a part of the thread guide frame.

A thread guide support 35 is secured to 100 and projects from each of the supporting bars 30—31, the vertical parts of these supports being of different lengths to locate the guides to direct the thread to the top of one thread form and to the bottom of 105 the other thread form. As both of the thread guides are of the same construction a description of one only will be given here-

in, it being understood that the description will apply to both of said guides. It will be understood that the thread is wound upon the form in a particular shape for subsequent use in a manner to be herein-after described.

Two cooperating thread holding jaws 36-37 are mounted upon the support 35, one of these jaws (the jaw 36 in the construction herein shown) being pivotally mounted, and the other jaw being preferably rigidly secured to the support. A jaw actuating rod 38 is attached at one end to the movable jaw 36 and at its opposite end said rod is in contact with a jaw actuator 39 mounted for sliding movement in the support 35, as shown in Figure 5 of the drawings. The actuator has a groove within which the end of the rod 38 is located, when the jaws are open. An adjusting screw 40 is secured in the end of the actuator to enable the proper movement of the actuator to be nicely determined, said actuator being operated by contact of the screw 40 with one of the bearings 32. At the termination of a winding operation of threads upon a thread form, the screw 40 appurtenant to that form will be carried against a bearing 32 and the actuator 39 will thereby have a sliding movement imparted to it to force the rod 38 out of the groove in which its end is located. This movement of the rod will cause the feed jaws to be brought into close contact thereby clamping a thread between them and the rotation of the thread form, continuing for an interval after this clamping action takes place, will result in the thread being broken. When the thread is thus broken it is held from backward movement by a thread holder in the form of a weighted lever 41 pivotally mounted as on the jaw 37.

Belt shifting mechanism for moving the belts 14-15 from the pulleys 13 to the pulleys 16, and vice versa comprises a belt shifter bar 42 slidably mounted in brackets 43 supported on the standards 11, said bar having splines 44 to prevent turning movement of the bar in its bearings. Belt shifters 45-46 are secured to said bar, projecting therefrom to engage the belts 14-15 as shown in Figure 1 of the drawings.

Thread form brakes 47-48, of any suitable material, as leather, project from brake posts 49-50 secured to the shifter bar 42, these brakes being suitably formed to engage the pulleys 16 when the belts are shifted therefrom and to stop rotation of said belts and consequently of the thread forms. The brake 47 projects from the under side of its post, while the brake 48 projects from the end of its post, and both brakes are suitably formed and located to move past the edge of and on to a pulley 65 for braking purposes after said brakes have

been moved beyond the edges of the pulleys to release them. The post 49 also serves as a belt shifting post and another belt shifting post 51 is secured to and projects from the bar 42, said post being located at times 70 in the path of movement of a belt shifting lever 52 pivotally mounted on the side of a standard 11 and having a reciprocating movement caused by movement of one of the posts 33 and at other times by a belt 75 shifting lever actuating post 53 secured to and projecting from the thread guide frame hereinbefore described, and as shown in Figure 2 of the drawings, the post 33, as hereinbefore described, comprising a part 80 of said thread guide frame, it being the post 33 located near said lever and in position to strike it as the thread guide frame is shifted from one position to another by engagement of the arm 29 with the threaded shaft, as 85 hereinafter described. A spring receiving arm 54 extends from the lever 52 to receive a belt shifting lever actuating spring 55 secured at its upper end to said frame and at its lower end to a standard 11, as shown 90 in Figure 1 of the drawings, the attaching points of said spring being so arranged that as the lever is swung on its pivot a straight line extending between said attaching points will pass to opposite sides of the pivot of 95 the lever and the spring will, therefore, impart an accelerating movement to the lever and complete such movement whenever the spring is moved past said pivot, this in a manner that will be readily understood. 100

Mechanism for opening and closing the jaws of the thread form comprises a jaw operating lever 56 appurtenant to each thread form, said levers being pivotally attached each at one end to a projection from 105 one of the brackets 43, and as shown in Figure 1 of the drawings. Each lever encircles one of the grooved actuators 24 and its lower end is in the path of movement of a thread form jaw actuator 57, herein shown 110 as a headed pin, resiliently mounted in a support therefor, such support being a post 58 secured to and projecting from the bar 31 at one end of the machine and the other support being the guide arm 29 at the opposite end of the machine, and as shown in Figure 2, of the drawings. An actuating handle 59 is secured to each of the levers 56, which levers are each manually operated in one direction and mechanically operated 115 by the actuator 57 in the opposite direction. 120

The operation of the machine, briefly stated, is as follows:

A thread form at the left hand end of the machine, as viewed in Figure 1, is in 125 condition for winding thread thereon, the thread, however, being omitted from the showing for sake of clearness. The jaws are open and the winding operation is understood as nearing its completion. The 130

thread form at the opposite end of the machine is in condition for removal of the wound mass therefrom, the jaws being closed and the jaw operating lever 56 being 5 in the position to which it has been manually moved to close said jaws for removal of the thread form therefrom. As the winding operation continues as to the thread form at the left hand end of the machine, 10 and is completed the adjusting screw 40 at the left hand end of the thread guide frame makes contact with the bearing 32 at this end of the machine, thereby moving the jaw actuator 39 to clamp the thread guide jaws 15 upon the thread being wound, as hereinbefore described, and the thread is thereby broken, as hereinbefore set forth. This operation, as it will be understood, has been caused by a movement of the thread guide 20 frame to the left, which movement is caused by the engagement of the thread guide arm 29 with the threaded shaft 27. At about the same time that the thread is broken, as above described, this movement of the 25 thread guide arm carries the post 33 at the right hand end of the machine against the lower end of the belt shifting lever 52, swinging said lever on its pivot and moving the upper end thereof toward the 30 right, thus gradually moving the belts 14 and 15 from the positions shown in Figure 1, and from the pulleys 16 and 13 at the left on to the pulleys 13 and 16 at the right, this belt shifting movement of the lever 52 35 being accelerated by the spring 55 just as soon as said frame is moved past the pivot of said lever, as hereinbefore described. This movement of the belt shifting mechanism also engages the brake 48 with its pulley 16, thereby quickly stopping rotation of the thread form. This operation of the belt shifting mechanism starts rotation of the thread form at the right hand end of the machine and in a manner to be presently 40 described as to such thread form.

The thread that has been deposited by the winding operation upon the thread form at the left hand end of the machine, and in a predetermined manner, is now in condition for removal, and the machine attendant inserts one of the branches of a doubled-wire core or form retainer 62 through the opening between the jaws of the thread form, and at the heels thereof, and the 45 wound mass of thread is thus located between the branches of said core so that when the formed mass is removed from the form it will be in the shape of loops on opposite sides of the core and as shown in Figure 6 50 of the drawing, and in condition for a twisting of the wires constituting the branches to secure the loops thereto. To remove the formed mass the attendant moves, by means of the handle 59, the lever 56 appurtenant 55 to the thread form referred to thus closing

the jaws of said form, and the mass being thus loosened it is slipped off at the ends of the jaws.

The thread from one of the spools 60 is now extended by the attendant and engaged in a notch 61 in the heel of one of the jaws, in which notch it is securely held, and the thread form is now in condition for another winding operation.

It will be understood that during the 75 operation of removal of the thread mass from the form as above described, the thread form at the opposite end of the machine has been undergoing a winding operation to wind a mass of thread thereon 80 and the thread guide frame has been gradually moving toward the right owing to engagement of the arm 29 with the threaded portion of the shaft 27. At a certain time, and after the thread form has been placed 85 in condition for another winding operation at the left of the machine as just above described, the jaw actuator 57 appurtenant to said thread form will be moved against the lever 56 at the left of the machine, and said lever will thereby be operated to move the actuator 24 to open the thread form jaws 90 in condition for a winding of a thread mass 95 thereon.

At the completion of movement of the thread guide frame toward the right, as hereinbefore described, the shifting of the belt on to the pulleys 13-16 at the right effected a reverse movement of the shaft 27 100 and also started rotation of the thread form at the right and in a direction opposite to that at which the thread form at the left was rotated, the thread being guided to the underside of the right thread form and to the upper side of the left thread form. This reversal of rotation of the shaft 27 causes a movement of the thread guide frame to the right and the winding of the thread from the inner to the outer end of the thread form 105 at the right, the rest of the operation being as above described with respect to the left thread guide, and the operation of the machine being continued as long as may be desired.

In accordance with the provisions of the patent statutes I have described the principles of operation of my invention, together with the device which I now consider to represent the best embodiment thereof, but I desire to have it understood that the device shown is only illustrative and that the invention may be carried out by other means.

I claim—

1. A winding machine comprising a 125 rotatable thread form, a thread guide supported in cooperative relation with respect to said thread form, thread winding mechanism including a driving element for winding thread upon said form, thread guide 130

- operating mechanism including a driving element therefor, a driving member, and means for connecting said driving member alternately with said driving elements whereby intermittent stopping of the rotation of each thread form is caused.
2. A winding machine comprising a plurality of rotatable thread forms, mechanism for winding thread upon said forms and including a driving element for each of said mechanisms, a thread guide for each of said forms, thread guide operating mechanism common to all of said guides and including a plurality of driving elements therefor, driving members, and means for alternately connecting each of said driving members with a thread winding driving element and with a thread guide driving element whereby intermittent stopping of the rotation of each thread form is caused.
3. A winding machine comprising a plurality of rotatable thread forms, mechanism for winding thread upon said forms and including a driving element for each of said mechanisms, a thread guide for each of said forms, thread guide operating mechanism including a plurality of driving elements therefor, driving members, and means for alternately connecting each of said driving members with a thread winding driving element and with a thread guide driving member whereby intermittent stopping of the rotation of each thread form is caused.
4. A winding machine including a plurality of rotatable thread forms, thread winding mechanism for each thread form and including a driving element for each mechanism, a thread guide for each thread form, thread guide operating mechanism including a driving element, driving members for operating said winding mechanism in opposite directions, and means for alternately connecting each of said driving members with a winding driving element and with a thread guide driving element whereby intermittent stopping of the rotation of each thread form is caused.
5. A winding machine including a plurality of rotatable thread forms, thread winding mechanism for each thread form and including a plurality of driving elements for said mechanisms a thread guide for each thread form, thread guide operating mechanism for moving said thread guides in opposite directions, driving members for operating said winding mechanisms in opposite directions, and means for alternately connecting the said driving members with a winding driving element and with a thread guide driving element whereby intermittent stopping of the rotation of each thread form is caused.
6. A winding machine including a winding mechanism, thread guide mechanism, a driving element included in said winding mechanism, a plurality of driving elements included in said thread guide mechanism, a driving member, and means for alternately connecting said driving member with the winding mechanism driving element and with the thread guide driving element.
7. A winding machine including a plurality of winding mechanisms, a thread guide mechanism common to both of said winding mechanisms, a driving element included in each of said winding mechanisms, a plurality of driving elements included in the said thread guide mechanisms, a plurality of driving members and means for alternately connecting said driving members with a winding mechanism driving element and with a thread guide driving element.
8. A winding machine including a plurality of winding mechanisms, thread guide mechanism common to both of said winding mechanisms, a driving element included in each of said winding mechanisms to drive said mechanisms in opposite directions, a plurality of driving elements included in said thread guide mechanisms, a plurality of driving members, and means for alternately connecting one of said driving members with a winding mechanism driving element and with a thread guide winding element.
9. A winding machine including a plurality of winding forms, thread guides for each of said thread forms, thread winding mechanism for each of said thread forms, each of said mechanisms including a driving element, thread guide operating mechanism for each thread guide, said thread guide operating mechanisms each including a driving element, a plurality of driving members and means for alternately connecting each of said driving members with a winding mechanism driving element and with a thread guide driving element.
10. A winding machine including a plurality of thread forms, thread guide mechanism common to both of said thread forms and including means for moving the thread guides in opposite directions, driving mechanism including a driving element for each thread form, driving mechanism for said thread guides and including driving element, a plurality of driving members, and means for alternately connecting each of said driving members with a driving element of said thread winding mechanism and a driving element of said thread guide mechanism.
11. A winding machine including a rotatable thread form, means for rotating said thread form, thread guide mechanism, means for operating said thread guide mechanism in one direction, means for operating it in an opposite direction, a driving member, and means for alternately connecting said driving member with the means for rotating the thread form and with the means for operating the thread guide in opposite directions.

12. A winding machine including a rotatable thread form, a rotating member for rotating said thread form, thread guide mechanism, a member rotatable independently of the thread form rotating member and to operate said thread guide mechanism in one direction, a driving member secured to the thread form rotating member, a driving member secured to the thread guide rotating member, and means for alternately operating said thread form rotating member and said thread guide operating member.
13. A winding machine including a plurality of rotatable thread forms, means for rotating each of said thread forms, thread guide mechanism, means for operating said thread guide mechanism in opposite directions, and means for alternately connecting each of said thread form rotating means with the means for operating said thread guide mechanism.
14. A winding machine including a plurality of rotatable thread forms, thread guide mechanism, a set of driving members appurtenant to each thread form and including a member to rotate said thread form and a member to operate said thread guide mechanism, means for driving each of said driving members, and means for alternately connecting each of said driving means with the driving members of each of said sets of driving members.
15. A winding machine including a rotatable thread form, a sleeve rotatably mounted to rotate said thread form, a driving member secured to rotate said sleeve, a spindle rotatably mounted in said sleeve, a driving member secured to rotate said spindle, thread guide mechanism operatively connected with said spindle, means for operating said driving members, and means for intermittently connecting said operating means with said driving members.
16. A winding machine including a plurality of thread forms, means for rotating each of said thread forms, and means for simultaneously stopping the operation of one of said rotating means and for starting another of said rotating means.
17. A winding machine including a plurality of thread forms, means for rotating each of said thread forms, thread guide mechanism common to all of said thread forms, means for operating said thread guide mechanism in opposite directions, and means operating concurrently with the movement of the thread guide in each direction to stop the operation of one of said thread guide rotating means and to start operation of another of said thread guide rotating means.
18. A winding machine including a thread form having collapsible members, means for rotating said form, means for automatically operating said members for one movement, and means for manually operating said members for an opposite movement.
19. A winding machine including a thread form having opening and closing jaws, means for automatically closing said jaws, and means for manually opening said jaws.
20. A winding machine including a rotatable thread form, means for rotating said form, a thread guide frame, mechanism for moving said frame in opposite directions and including an operating member, a driving member, and means for alternately connecting said driving member with said thread form rotating means and with said thread guide frame operating member.
21. A winding machine including a plurality of rotatable thread forms, means for rotating each of said forms, a thread guide frame, mechanism for moving said frame in opposite directions and including an operating member appurtenant to each of said thread forms, a driving member for each of said forms, and means for simultaneously connecting said driving members alternately with said thread form rotating means and with said thread guide frame operating member.
22. A winding machine including a rotatable thread form, means for rotating said form, a thread guide frame, mechanism for operating said frame and including an operating member, a driving member, and mechanism operatively connected with said thread guide frame to alternately connect said driving member with said thread form rotating means and with said thread guide operating member.
23. A winding machine including a plurality of thread forms, a thread guide frame, a set of operating members appurtenant to each thread form, one of said members operating to rotate the thread form and the other to operate the thread guide frame, said thread guide frame operating member operating to move the thread guide frame in opposite directions, a driving member for each set of operating members, and mechanism operatively connected with said thread guide frame to alternately connect the members of each set of operating members.
24. A winding machine including a thread form with collapsible members, means for rotating said form, a thread guide frame, means for operating said frame, and means connected with said frame for actuating the members of said collapsible thread form.
25. A winding machine including a thread form, thread guide mechanism, means for rotating the thread form, means for operating the thread guide mechanism, a driving member, means for alternately

- connecting said driving member with the means for rotating the thread form and the means for operating the thread guide, a brake, and means for automatically moving the brake into position to retard movement of the thread form rotating means.
26. A winding mechanism including a thread form, thread guide mechanism, means for rotating the thread form, means for operating the thread guide mechanism, a shifting member operatively connected with the thread guide mechanism, a driving member operatively connected with said shifting member for alternate connection with the thread form rotating means and the thread guide mechanism operating means, and a brake operatively connected with said shifting member and operated thereby to retard rotation of said thread form.
27. A winding machine including a rotatable thread form, means for rotating said form, a thread guide support, means for operating said guide support, a thread guide mounted on said support to guide thread to said form, said guide including clamping jaws, and means for operating said jaws to clamp a thread between them.
28. A winding machine including a rotatable thread form, means for rotating said form, a thread guide support, means for operating said support, a thread guide mounted on said support to guide thread to said form, said guide including clamping jaws, and means actuated by movement of said thread guide support to clamp the thread between said jaws.
29. A winding machine including a rotatable thread form, means for rotating said form, a thread guide support, means for operating said support, a thread guide mounted on said support to guide thread to said form, said guide including clamping jaws that are normally open during the winding operation, and means for closing said jaws to clamp a thread between them at a completion of the winding operation.
30. A winding machine including a thread form, means for rotating said thread form, a thread guide frame, a plurality of members for moving said frame in opposite directions, a plurality of driving members for operating said thread guide moving members, means for disconnecting said driving members from said thread guide moving members, and connections between said driving members and said thread guide frame for operation of said driving members by the movement of said thread guide frame.
31. A winding machine including a plurality of thread forms, means for rotating said forms, a thread guide frame, a set of members appurtenant to each thread form, one of said members of each set to rotate a thread form and the other of said members
- to operate said thread guide frame, a driving member for each of said sets of members, means for alternately connecting each of said driving members with the members of each of said sets, and an operative connection between said connecting means and said thread guide frame for operation of said connecting means by the movement of said thread guide frame.
32. A winding machine including a thread form comprising two members with an opening between them to receive one of the branches of a form retainer, a thread guide, means for causing relative movement between said form and guide to cause a thread to be wrapped about the form, and means for causing a relative movement between said members to cause the thread to be wrapped around the form along its length.
33. A winding machine including a thread form comprising two members with an opening between them to receive one of the branches of a form retainer, a thread guide, means for causing relative movement between said form and guide to cause the thread to be wrapped about the form, and means for operating the guide to cause the thread to be wrapped about the form along its length.
34. A winding machine including a plurality of thread forms, mechanism for winding thread upon one of said forms along its length while the operation of winding thread upon another of said forms has ceased, and means for automatically stopping the winding operation upon said thread form.
35. A winding machine including a plurality of thread forms, each comprising two members with an opening between them to receive one of the branches of a form retainer, means for causing a winding operation of a thread upon one of said forms while the winding operation upon the other of said forms has ceased, and means for automatically stopping said winding operation.
36. A winding machine comprising a rotatable thread form, a thread guide supported in cooperative relation with respect to said thread form, thread winding mechanism including a driving element for winding thread upon said form, thread guide operating mechanism including a plurality of driving elements therefor, a plurality of driving members, and means for alternately connecting and disconnecting one of said driving members with and from a thread guide driving element and for alternately connecting and disconnecting one of said driving members with and from said thread winding driving element.
37. A winding machine comprising a plurality of thread forms, a thread guide supported in cooperative relation with re-

pect to each of said thread forms, thread winding mechanism including a driving element for each of said thread forms to wind thread thereon, thread guide operating mechanism including a plurality of driving elements therefor, a plurality of driving members, and means for alternately connecting and disconnecting each of said driving members with and from each of said thread 10 winding driving elements and with and from each of said thread guide driving elements.

38. A winding machine comprising a plurality of thread forms, a thread guide supported in cooperative relation with respect to each of said thread forms, thread winding mechanism including a driving element for each of said thread forms to wind thread thereupon, thread guide operating mechanism including a plurality of driving 15 elements therefor both connected to each of said thread guides, a plurality of driving members, and means for alternately connecting and disconnecting each of said driving 20

members with and from each of said thread winding driving elements and with and from each of said thread guide driving elements. 25

39. A winding machine comprising a plurality of thread forms, a thread guide supported in cooperative relation with respect to each of said forms, thread winding mechanism including a driving element for each of said thread forms to wind thread thereupon, thread guide operating mechanism including a plurality of driving elements therefor to continuously operate all of 30 said thread guides to move them back and forth relatively to said forms, a plurality of driving members, and means for alternately connecting and disconnecting said driving members with and from each of said 35 thread winding driving elements and with and from each of said thread guide driving elements to impart intermittent rotation to each of said thread forms and to continuously operate each of said thread guides. 40

ANTON VAN VEEN.
